(57) **CLAIM**

The ornamental design for an electronic projection system, as shown and described.

DESCRIPTION

FIG. 1 is a front perspective view of the electronic projection system;
FIG. 2 is a front elevation view thereof;

FIG. 3 is a rear elevation view thereof;

FIG. 4 is a top plan view thereof;

FIG. 5 is a bottom plan view thereof;

FIG. 6 is a left side elevation view thereof; and,

FIG. 7 is a right side elevation view thereof.

The portions of the article in broken lines are shown for illustrative purposes only and form no part of the claimed design.
